UNITED STATES PATENT OFFICE.

JOHN HAYS HAMMOND, JR., OF GLOUCESTER, MASSACHUSETTS.

TORPEDO.

Application filed August 2, 1913, Serial No. 782,590. Renewed August 25, 1923.

My invention relates to submarine automobile torpedoes and to their protection from hostile fire, as well as to means for increasing their stability and speed, and for 5 maintaining them at any desired depth of submergence, and relates more particularly to torpedoes controlled by radiant energy.

In the accompanying drawings:—

Figure 1 shows a side view of one of my 10 torpedoes.

Figure 2 shows an end view of one of my torpedoes.

Figure 3 shows a side view, partly in section, of one of my torpedoes.

Figure 4 shows a top view partly in section, of one of my torpedoes.

Figure 5 shows a side view of one of my torpedoes with a modified form of masts and antenna.

Figure 6 shows a top view of one of my torpedoes.

Figure 7 shows an end view of one of my torpedoes, with a modified form of masts and antenna.

Figure 8 shows a cross-sectional view of one of my torpedoes.

In the figures, a torpedo with a spindle-shaped hull T has a deep keel F with a heavy bulb K arranged to give stability. A superstructure S is filled with cork, or similar substance, and serves to protect the vital parts of the torpedo from hostile fire, as well as to give it buoyancy. Planes or rudders P, P¹, P², P³, P⁴, P⁵, P⁶, P⁷ and P⁸, with horizontal axes, at both ends of the hull, can be set at any suitable angle, so that as the torpedo goes ahead it can be made to run at any depth desired, the vertical component of the pressure of the water on the planes 40 being balanced by the buoyancy of the vessel. The torpedo may thus float at a certain water-line when at rest, but when running will be forced down by the planes to a deeper draft, so giving more protection to the hull. 45 and machinery. These planes may be attached to the superstructure instead of to the hull. A manhole J, with watertight cover H, affords a means of entrance through the superstructure into the interior 50 of the hull.

An antenna A, for the reception of radiant energy, is supported on masts, each of which consists of a lower portion, M and M², preferably hollow and made of metal, 55 and an upper portion, M¹ and M³, preferably made of wood. These masts, however,

may be made of any suitable material. Openings V and V¹ in the lower portion of the masts, serve to ventilate the interior of the hull, and a fan or blower B either exhausts the foul air and gases from the interior, or brings in fresh air.

In Figures 5, 7 and 8, where a modified form of masts and antenna is shown, A¹ is an antenna supported on a plurality of 60 masts, each of which may consist of a single piece, or of two parts, as shown. M⁴, M⁶, M⁸ and M¹⁰ are the lower portions of these masts, and M⁵, M⁷, M⁹ and M¹¹ are the upper portions. These masts are connected by a 70 supporting framework or latticework consisting of uprights N, N—N, of inclined or diagonal members O, O—O, the latter being either rigid or flexible, and of a horizontal member Q, Q, Q, either rigid or flexible. 75 In case one or more of the masts are shot away, this framework or latticework will support the others and maintain the antenna in working condition. The members of the framework may consist of metal, wood, 80 wire or rope, or any other suitable material.

The torpedo itself may be made of any suitable material, and while the shapes of its parts are in general such as described and shown, I do not limit myself to these precise shapes, but may employ any suitable ones which lie with the scope of my invention.

I may employ any suitable radio receiving apparatus in connection with my antenna, 90 and I may use any appropriate means for propelling and steering my torpedo.

In general, I do not confine myself to the particular apparatus and forms here shown, but various changes and modifications, within the knowledge of those skilled in the art, may be made in the particular apparatus and forms shown and described herein, without departing from the spirit of my invention, provided the means set forth in 100 the following claims be employed.

Having thus described my invention, I claim:—

1. In a torpedo, the combination of a hull tapered toward both ends, a superstructure intermediate the ends of the hull, having a width less than the width of the hull, and having its upper surface substantially parallel with the longitudinal axis of the hull, 105 said superstructure containing buoyant, shot-absorbing material, a fin bulb keel arranged centrally below the hull, and rudders, turn-

ing on horizontal axes, adapted to be set at any angle of inclination.

2. In a torpedo, the combination of a hull tapered toward both ends, a superstructure intermediate the ends of the hull, said super-

structure containing buoyant, shot-absorbing material, a heavy keel arranged centrally below the hull, masts consisting of a lower,

hollow part, extending through the super-structure to the hull and an upper solid part, 10 and rudders turning on horizontal axes adapted to be set at any angle of inclina-

tion.

This specification signed this 29th day

of July, A. D., 1913.

JOHN HAYS HAMMOND, JR.
